UNITED STATES PATENT OFFICE.

NICKOLAUS ZINS, OF EVANSVILLE, INDIANA, ASSIGNOR TO ZINS BROTHERS,
OF SAME PLACE.

CHILL-MOLD FOR DOG-IRONS.

SPECIFICATION forming part of Letters Patent No. 289,366, dated November 27, 1883.

Application filed August 23, 1883. (No model.)

To all whom it may concern:

Be it known that I, N. ZINS, a citizen of the United States, residing at Evansville, in the county of Vanderburgh and State of Indiana,

5 have invented certain new and useful Improvements in Chill-Molds for Dogs; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a representation of this invention, and is a top view closed over the dog. Fig. 2 is a top view of the mold open and without the dog. Fig. 3 is a vertical section through the mold and the dog.

20 Fig. 4 is a perspective detail, showing that end of the leg which is inserted in the mold.

This invention has relation to chill-molds for casting andirons or dog-irons to be used upon the hearth; and it consists in the novel 25 construction and arrangement of devices, as will be hereinafter fully described, and particularly pointed out in the claim appended.

Referring by letter to the accompanying drawings, *a* designates the bed-plate of the 30 chilled or cast-iron mold or former, the dog-iron being made therein, except the leg *b*, which may be cast separately, and inserted into the leg-holder *c*, formed in two sections, *d d*, upon the hinged covers *e e'* of the mold.

35 The covers *e e'* are hinged at *f*, and swing laterally over the recesses in the bed-plate.

g g designate the buttons for securing the

covers in a closed position, and *h h* are metal staples, which may be engaged by a hook or otherwise to manipulate the covers while hot. 40 *i* designates the sprue of the chill-mold, and *k* is the vent or riser for the escape of the air as the metal is poured in at the sprue. Without the covers the casting will be imperfect by reason of insufficient metal or other cause, 45 and never square, full, and complete as when the covers are used.

m indicates a depression or recess in the bed of the mold, centrally beneath the leg-holder *c*. When the sections *d* are closed upon 50 the mold, this recess receives the lower end of the said leg.

The mold-cavity may be ornamented in any suitable style to suit the taste of the public.

Having thus fully described my invention, 55 what I claim as new, and desire to secure by Letters Patent, is—

The combination, with the base *a*, of the chill-mold provided with the mold-cavity, and carrying the buttons *g g* and one-half of the 60 sprue *i* of the hinged laterally-swinging covers *e e'*, pivoted at *f* to the front end of the base *a*, and having each in their inner edges the half-riser *k*, the half-leg-holder *d*, and the staples *h*, and the half-cover *e'* being provided in 65 its inner edge, near its rear end, with the half-sprue *i*, substantially as specified.

In testimony whereof I affix my signature in presence of two witnesses.

NICKOLAUS ZINS.
